(57) **CLAIM**

The ornamental design for a car seat cover, as shown and described.

DESCRIPTION

FIG. 1 is a front, left and top perspective view of a car seat cover, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of portion 9 shown in FIG. 1; and,

FIG. 10 is an enlarged view of portion 10 shown in FIG. 2.

The broken lines in the drawings illustrate the portions of the car seat cover, which form no part of the claimed design. The dot-dash broken lines in FIGS. 1, 2, 9, and 10 depict boundary lines of the enlargement views and form no part of the claimed design.
